UNITED STATES PATENT OFFICE.

HARRIET RUBENS, OF CHICAGO, ILLINOIS.

HAIR-PIN AND MANICURE IMPLEMENT.

SPECIFICATION forming part of Letters Patent No. 729,898, dated June 2, 1903.

Application filed October 13, 1902. Serial No. 127,036. (No model.)

To all whom it may concern:

Be it known that I, HARRIET RUBENS, a citizen of the United States, residing at Chicago, in the county of Cook and State of Illinois, have invented a new and useful Hair-Pin and Manicure Implement, of which the following is a specification.

The primary object of my invention is to provide a manicure implement in a form that will adapt it to be stowed away when out of use by sticking it into the hair on a woman's head, where it will be conveniently accessible when desired for use on the finger-nails, besides, incidentally, affording means for fastening the hair.

The ordinarily inadequate provision in women's wearing-apparel of pockets in which to stow articles they desire to have handy for toilet purposes renders inconvenient the carrying about with them of such articles. By providing a manicure implement as a hair-pin in a form adapting it to penetrate the hair, which it may also serve to hold up and, if desired, to ornament, I compensate for the lack of a pocket, so far as such an article is concerned, and enable women to carry with them a suitable manicuring implement without inconvenience where it is most conveniently accessible at all times.

Referring to the accompanying drawings, Figure 1 illustrates my improved article applied as a hair-pin. Fig. 2 is a perspective view of the article, and Fig. 3 a section taken at the line 3 on Fig. 2 and viewed in the direction of the arrow.

A is a hair-pin formed in the shape represented in the drawings, or in any other desired shape, of metal or of any other suitable material. One end of the device is beveled, as shown, to point it and form it into an implement *a*, adapted to be inserted under a finger-nail for cleaning it. The opposite end of the device is expanded into a head and is formed into the implement *b*, adapted for use in pushing back the cuticle on the finger-nails. While the cuticle-pushing implement *b* may for my purpose be provided in any of various forms, I prefer to provide it in the form in which it is illustrated, wherein it is divided into two blades *b'* and *b''*, each beveled at its extremity and longitudinally con-

cavo-convex, as shown, or, at least, longitudinally concave on one side, to cause it to conform to the contour of the nails, and the outer corners of the blades should be rounded, 55 as shown. By thus forming the implement *b* it serves for pushing back the cuticle not only at the base of a finger-nail but also at the corners and without scratching or disfiguring the surface of the nail.

The face of the head portion of the pin may be ornamented, the letter *M* being applied in Fig. 2 to denote the space referred to for ornamentation.

I claim as my invention—

1. As a new article of manufacture, a hair-pin provided at one end with a cuticle-pushing manicure implement, substantially as described.

2. As a new article of manufacture, a hair-pin provided at one end with a beveled nail-cleaning manicure implement, substantially as described.

3. As a new article of manufacture, a hair-pin provided at its opposite ends, respectively, with a cuticle-pushing manicure implement and a beveled nail-cleaning manicure implement, substantially as described.

4. As a new article of manufacture, a hair-pin having an expanded end beveled toward 80 its extremity and rounded at its corners and forming a cuticle-pushing manicure implement, substantially as described.

5. As a new article of manufacture, a hair-pin having an expanded end divided into two 85 blades, longitudinally concave on their under sides and beveled toward their extremities, forming a cuticle-pushing manicure implement, substantially as described.

6. As a new article of manufacture, a hair-pin beveled at one end to form said end into a nail-cleaning manicure implement, and having its opposite end expanded and divided into two longitudinally concavo-convex blades beveled toward their extremities and 95 rounded at their corners and forming a cuticle-pushing manicure implement, substantially as described.

HARRIET RUBENS.

In presence of—

L. HEISLAR,
ALBERT D. BACCI.
